Design No. 517.

John W. Wheeler and O. B. Latham

Design for a Pump-Curb Patented November 2, 1882.

John W. Wheeler & Obadiah B. Batham of Seneca Falls, N.Y.
Letters Patent No 577 Dated Nov. 2nd 1852

The schedule referred to in these Letters Patent and making part of the same

To all whom it may concern:

Be it known that we, John W. Wheeler and Obadiah B. Batham, both of Seneca Falls, in the County of Seneca, State of New York, have invented a new combination of forms and figures as hereinafter described, intended as an ornamental design for the curb of a chain pump of which the following is a full description, reference being had to the annexed drawing which forms a part of this specification.

The curb of the chain pump is made of cast iron and consists of four pieces exclusive of the spout. Two of these pieces placed together form the cap and the remaining two the main part of the curb, each piece being curved at its sides about five inches when united leave a space within the curb about ten inches in width. As both sides of the curb are alike, the single drawing annexed will represent all the ornamental work claimed as new.

Two of the pieces placed together form the cap of the curb (A, B, C in the annexed drawing) which is semicircular and having across it a series of curved rolls or ribbed work as seen at B, B, B, under & within the ribbed work is ornamental open or lattice work filling up the sides of the cap. Around its bottom A, B, is a series of pendants or hanging drapery. The two remaining pieces when joined form the sides of the curb, one of which is represented by D, E, F, G, and as there exhibited, each side is ornamented with a double arched window surmounted by a star. The lights and each are represented by panel work and the part immediately above represents lattice or open work. Below the window are several mouldings or projections forming a proper base for the curb. The drawing annexed represents either side of the curb, and as an end view would present no new, or additional ornaments it is omitted.

What we claim as our invention and desire to secure by Letters Patent, is the combination and arrangement of ornamental forms, carvings and configurations as represented in the annexed drawing (Fig. 1,) making an ornamental design for the curb of a chair pump.
